CLAIM

The ornamental design for a tripod, as shown and described.

DESCRIPTION

FIG. 1 is a perspective view of a tripod showing our new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is a partially enlarged view of FIG. 1;

FIG. 10 is another partially enlarged view of FIG. 1;

FIG. 11 is a partially enlarged view of FIG. 2;

FIG. 12 is a partially enlarged view of FIG. 7;

FIG. 13 is a partially enlarged view of FIG. 8;

FIG. 14 is a tripod in an alternate folded configuration; and,

FIG. 15 is a bottom view thereof.

The broken lines in the figures depict portions of the tripod and the circled broken lined areas are for the purpose of disclosing enlarged detailed views, none of which form no part of the claimed design.

1 Claim, 15 Drawing Sheets
